UNITED STATES PATENT OFFICE.

CHARLES H. FRENCH, OF CANTON, MASSACHUSETTS, ASSIGNOR TO FRENCH & WARD, OF NEW YORK, N. Y., A FIRM.

DESIGN FOR KNIT FABRIC.

No. 37,936.

Specification for Design.

Patented April 3, 1906.

Application filed January 31, 1906. Serial No. 298,881. Term of patent 14 years.

To all whom it may concern:

Be it known that I, CHARLES H. FRENCH, a citizen of the United States, residing at Canton, in the county of Norfolk and State of Massachusetts, have invented a new, original, and ornamental Design for a Knit Fabric, of which the following is a specification, reference being had to the accompanying drawing, forming a part thereof.

The figure of the drawing is a plan showing my new design.

I claim—

The ornamental design for a knit fabric, as shown.

CHARLES H. FRENCH.
